TOWEL UNWINDING AND FOLDING MACHINE

Paul W. Jespersen, Wilmette, Ill., assignor to
American Linen Supply Co., Chicago, Ill., a
corporation of Nevada

Application September 30, 1950, Serial No. 187,766

12 Claims. (Cl. 342—55)

1

The present invention relates in general to automatic towel folding machines and more particularly to a novel continuous roll container adapted to be utilized in an automatic towel unwinding and folding machine of the type disclosed in my copending application Serial No. 148,777, filed March 10, 1950.

The machines of the type noted above are utilized by large commercial laundries and linen supply companies in order to prepare soiled toweling of the continuous roll type for a laundering operation by unwinding the soiled toweling from the roll and folding it into zigzag layers of convenient lengths. Thereafter the folded layers of toweling are gathered together transversely to the length thereof and loosely tied together at one or more points, in order to form a relatively loose bundle which may then be deposited into a washing machine.

In the unwinding and folding machine disclosed in the above mentioned copending application a soiled roll of approximately fifty yards of toweling is placed into a V-shaped open top supporting trough or container, and the outer web of the toweling is unwound from the roll and fed into the machine in such a manner that the outer web, as it is drawn from the roll, passes directly across the open top of the V-shaped trough. With this arrangement the web of the toweling, as it is drawn across the open top of the trough, functions as a cover therefor and thereby prevents the roll from being inadvertently yanked, pulled or bounced out of the trough during the relatively high speed unwinding operation.

While this method of supporting and unwinding a continuous roll of the toweling is quite satisfactory for the average soiled roll, it has been found that certain rolls such as those returned from packing houses, garages, manufacturing plants, etc. are so extremely soiled with grease, fat, blood, oil and other foreign matter deposited thereon that adjacent layers of the rolled toweling are frequently stuck together as the foreign matter dries and, consequently, will not unwind properly as the web of the toweling is withdrawn from the roll.

Accordingly, it is the primary object of the present invention to provide in a roll towel unwinding and folding machine an improved roll towel supporting mechanism which is arranged to automatically rotate the roll of toweling in the unwinding direction, in the event stuck together adjacent layers of the toweling are encountered as the outer web thereof is withdrawn by the unwinding mechanism in order to separate the layers which are stuck together by pulling them apart.

It is a further object of the invention to provide in a machine of the type noted an improved mechanism for positively retaining the roll of soiled toweling in a supporting mechanism as the outer web of the roll is withdrawn therefrom by the unwinding and folding mechanism.

2

It is still a further object of the invention to provide in a machine of the type noted a novel driving mechanism for positively rotating the soiled roll of toweling in an unwinding direction whenever the roll is pulled from its normal position in the supporting mechanism into engagement with the driving mechanism.

Further objects and features of the invention pertain to the particular structural arrangement 10 of the improved roll towel supporting mechanism for a towel unwinding and folding machine whereby the above outlined objects and additional operating features are attained.

The present invention, both as to the organization 15 and method of operation, together with further objects and advantages thereof, will best be understood by reference to the following specification taken in connection with the accompanying drawings in which:

20 Figure 1 is a partial front elevation of the improved roll towel supporting mechanism, and illustrates the manner in which the mechanism is supported upon the structure of a towel unwinding and folding machine of the type disclosed in 25 the above-mentioned copending application;

Fig. 2 is a sectional view taken along line 2—2 of Fig. 3 and illustrates the details of the towel supporting container and the driving mechanism therefor;

30 Fig. 3 is an enlarged top view of the mechanism shown in Fig. 1 with certain parts thereof omitted in order more clearly to illustrate the structural details of the mechanism;

Fig. 4 is an enlarged view taken along line 4—4 35 of Fig. 3 of the driven roller and the support provided in the housing of the towel supporting mechanism, and illustrates the manner in which the tension of the flat belt for rotating the roll of toweling may be adjusted; and

40 Fig. 5 is a sectional view taken along line 5—5 of Fig. 4 and illustrates the structural details of the towel unwinding roller and the flat belt adjusting arrangement.

Referring now to Fig. 1 it will be seen that the 45 supporting frame structure for the towel unwinding and folding machine comprises a pair of spaced apart channel members 21a, 21b and a channel brace 22 secured therebetween. Each of the channel members 21a and 21b extend down- 50 wardly and outwardly below the brace 22 in order to provide two spaced-apart supporting legs for the machine which may be anchored to the floor in any desired manner. Further details of the supporting structure, noted above, and the details 55 of the unwinding and folding mechanism 24, supported between the channel members 21a and 21b, are disclosed and described in the above-mentioned copending application. However, in order to fully understand the improved towel supporting mechanism, a brief description will first be given of the unwinding and folding mechanism 24 to which the improved towel supporting mechanism is secured.

The mechanism 24 includes left and right side plates 26a and 26b, which are respectively the front and rear plates of the mechanism, as seen in Figs. 1 and 3. As is best illustrated in Fig. 3 the right side plate 26b is secured to the right channel member 21b and, as is best illustrated in Fig. 1, the opposite end of plate 26b is also secured to the left channel member 21a. Except for the bottom portion of the folding mechanism 24 and the sloping surface thereof shown in the upper right hand portion of Fig. 1, the housing including the side plates 26a and 26b is entirely enclosed. The mechanism 24 also includes a driven roller 27 which is rotatably supported between the respective side plates 26a and 26b. One end of the shaft for the driven roller 27 extends through the side plate 26b as is best illustrated in Fig. 3, and supports a large motor driven belt pulley 28 and a somewhat smaller oscillator drive belt pulley 29. These pulleys are rigidly secured to the shaft of the roller 27. In addition to the foregoing, the end of the roller 27, which is located adjacent to the right side plate 26b, is provided with a V-shaped trough 27a to form a pulley for supporting the belt for driving the towel unwinding rollers mounted in the roll supporting mechanism as will be described hereinafter.

In view of the above description of the driven roller 27 and the arrangement for rotatably supporting the same between the side plates 26a and 26b, it will be understood that the roller 27 and the pulleys 28 and 29 will rotate at the same speed during the operation of the mechanism.

A pressure roller 30 is rotatably mounted parallel to and adjacent to the driven roller 27 on oppositely disposed pivoted supporting brackets 31a and 31b. These brackets are pivotally mounted on the plates 26a and 26b so that the roller 30 may be moved away from the driven roller 27 but the brackets 31a and 31b are tensioned so that the pressure roller 30 normally presses against the driven roller 27. During the operation of the mechanism the outer web of the toweling, which is being unwound from the soiled roll 53, is clamped between the adjacent surfaces of the driven roller 27 and the pressure roller 30. With this arrangement the driven roller functions to pull the outer web of toweling from the roll.

The unwinding and folding mechanism 24 also includes an oscillating mechanism for simultaneously oscillating the spreader plates 32a and 32b, as is best illustrated in Fig. 2. The above noted spreader plates are independently mounted at their upper ends for simultaneous pivotal movement under control of a pair of spaced apart links 33a and 33b, a common yoke member 34 and a driven mechanism therefor, which includes a pulley 35, a pair of cooperating gears 36 and 37, a crank shaft 38 and a crank 39. The detailed structural arrangement of the oscillated drive mechanism is also fully described in the above noted copending application.

A motor 40 is secured to the top portion of the mechanism 24 for driving the various parts of the unwinding and folding mechanism 24. More specifically, the motor 40 is provided with a drive pulley 41 which is coupled to the previously noted large motor drive pulley 28, secured to the shaft of the driven roller 27, by means of a V-shaped drive belt 42. In addition to the foregoing, a V-shaped belt 43 is provided for coupling the previously noted small oscillator belt pulley 29, which is also secured to the shaft of the driven roller 27, and the pulley 35.

In view of the above description it will be understood that the motor 40 will rotate the driven motor 21 by means of the belt 42, and it will also rotate the pulley 35 by means of the belts 42 and 43. A small gear 36 is rigidly secured to the mounting shaft for the pulley 35, so that the rotation of the pulley 35 will also be transmitted by the gear 36 to the larger cooperating gear 37. At this point it should be noted that the cooperating gear 37 is secured to one end of the previously noted crankshaft 38, and that the crank 39 is secured to the opposite end of the crankshaft 38. Consequently the rotary movement of the gear 37 causes the crank 39 to rotate about the axis of the crankshaft 38. Since the common yoke 34 is rotatably secured to the extended end of the crank 39, as is best illustrated in Fig. 2, it will oscillate back and forth with a piston-like movement in order to control the oscillating movement of the spreader plates 32a and 32b. The opposite ends of the yoke 34 are pivotally secured to the mid-points of each of the spaced-apart links 33a and 33b, and the opposite ends of each of the links 33a and 33b are respectively pivotally secured to the spreader plates 32a and 32b. Therefore, as the crank 39 revolves under control of the crank shaft 38, the yoke 34 causes the spreader plates 32a and 32b to oscillate between two oppositely disposed predetermined positions on their upper pivoted mounting supports. As the web of the toweling is pulled by the driven roller 31 and dropped upon a work surface it passes between the spreader plates 32a and 32b and, due to the oscillatory movement of the spreader plates, the web of toweling is directed so that it automatically falls in folded layers approximately three feet in length upon a suitable work surface.

A description will now be given of the structural details of the continuous roll towel supporting mechanism which is secured to the right side of the unwinding and folding mechanism 24 as seen in Fig. 1. This mechanism includes a pair of side plates 50a and 50b, as is best illustrated in Fig. 3, which are secured respectively to the previously noted side plates 26a and 26b of the folding mechanism 24 by a plurality of bolts 51. A roll supporting bottom cover 52 extends between and is secured to the side plates 50a and 50b. This bottom cover is formed so that it is curved along a radius that conforms substantially to the radius of a full roll of soiled toweling 53. A top cover 54 is also provided which extends between and is secured to the side plates 50a and 50b. The last-mentioned cover is formed so that it is curved downwardly at its right edge, as is seen in Fig. 2, and abuts against the upper edge of the bottom cover 52. The upper surface of the top cover 54 is also curved downwardly at its left edge between the side plates 50a and 50b to form both a protecting guard which overhangs a pair of rotatable towel unwinding rollers 63 and 64 and a guide for directing a roll of toweling, deposited into the open top of the mechanism, into engagement with the gate 56 in the manner to be described herein-after.

A gate assembly is provided in the bottom portion of the towel supporting mechanism which includes a gate mounting bracket 55, a gate member 56, including the portions 56a, 56b, 56c and 56d, and a pair of stiffening brackets 57a and 57b. At the outset it should be noted that the gate mounting bracket 55 of this assembly is pivotally secured at opposite ends on a pair of pivot

pins 60a and 60b, carried by the respective side plates 50a and 50b. The gate 56 is secured to the gate mounting bracket 55, as is best illustrated in Figs. 2 and 3, by means of screws or the like to provide a substantially rigid gate for the pivotally mounted gate assembly. A lip 56a is formed at one edge of the gate 56 so that it will engage the left free end of the bottom cover 52. In order to retain the gate assembly tensioned in a counterclockwise direction about the pivot pins 60a and 60b, as is illustrated in Fig. 2, a pair of coil springs 61a and 61b are provided which are secured at opposite ends to the gate mounting 55 and to the combination wall panel and towel guide member 61. In passing it should be noted that the towel guide member 61 extends between the side plates 26a and 26b and is secured thereto between the side plates 50a and 50b by means of the previously noted bolts 51. A pair of bars 61c and 61d are secured to the panel 61 adjacent to the lower edge thereof to guide the roll of toweling 53 during the tilting movement of the gate 56. The upper portion of the combined wall panel and combined wall guide panel 61 is curved to the left, as is shown in Fig. 2, to overhang at least a portion of the driven roller 27 and it is arranged so that the web of the toweling 53 will be directed over a portion of the surface of the roller 27 during the unwinding operation of the mechanism.

Referring again to the gate assembly, it will be seen that it may be rotated in a clockwise direction about the pivot pins 60a and 60b, as is illustrated in Fig. 2, to a position that will align the upper surface 56b of the gate 56 with the upper surface of the bottom cover 52. In order to limit the clockwise rotation of the gate assembly to the position noted above, a pair of stop members 62a and 62b are respectively provided in the side plates 50a and 50b, as is best illustrated in Figs. 2 and 3. These stop members are positioned on the above noted side plates so that the under surface of the gate 56, at a point substantially adjacent to the free end of the gate mounting bracket 55, will engage the stop pins when the gate assembly is rotated in a clockwise direction to a point where the top surface 56b of the gate 56 is in substantial alignment with the upper left hand edge of the bottom cover 52.

In addition to the foregoing, the continuous roll towel supporting mechanism is provided with a pair of towel unwinding rollers 63 and 64, and a continuous flat belt 65. Referring now to the roller 63, it will be seen that the shaft 63a therefor is mounted at opposite ends in the roller bearing caps 66a and 66b secured respectively to the side plates 50a and 50b. The upper end of the shaft 63a, as is seen in Fig. 3, extends through the side plate 50b and rigidly supports a drive pulley 67. Since the roller 63 and the pulley 67 are rigidly secured to the shaft 63a they freely rotate as a unit in the bearing mountings 66a and 66b.

Referring now to the roller 64 it will be seen, by reference to Figs. 3, 4 and 5, that this roller is adjustably mounted so that the distance between the surfaces of the rollers 63 and 64 may be varied. At the outset it should be noted that the roller 64 is mounted on a shaft 64a which, at the opposite ends thereof, is mounted in the roller bearings 68a and 68b. The roller bearings 68a and 68b are, in turn, secured to the adjustable bearing caps 69a and 69b. Referring now particularly to Figs. 4 and 5 it will be seen that the upper end of the bearing cap 69a is se-

cured to the side plate 50a by means of the bolt 70a. At its lower end the bearing cap 69a is secured to a belt tightening swivel 71a by means of a plurality of lock nuts 72. In order to permit the lower portion of the bearing cap 69a to be rotated about a pivot point formed by the bolt 70a, a cooperating cut-out 73a is provided in the wall of the side plate 50a. The adjustment of the position of the bearing cap 69a is controlled by means of the belt tightening bolt 74a and the lock nut 75a. In this connection it should be noted that the belt tightening bolt 74a is inserted through a lug 76a formed in the side plate 50a and threaded through cooperating threads provided in the belt tightening swivel 71a, and is locked in place by the lock nut 75a. In order to adjust the position of the roller 64 the lock nut 75a may first be loosened and thereafter the bolt 74a is turned in either direction. After the roller 64 has been adjusted to take up any slack in the flat belt 65 encircling the roller 63 and the roller 64, the lock nut 75a may be tightened. Although the description of the adjustable arrangement for the roller 64 has been limited to the left end thereof, by reference to the enlarged views of Fig. 4 and Fig. 5, it will be appreciated that a corresponding adjusting arrangement is also provided at the opposite end of the roller 64. Referring again to Fig. 3, it will be seen that the shaft 63a for the roller 63 is provided with a drive pulley 67, and that the latter pulley is coupled to the driven roller 27 of the towel unwinding and folding mechanism 24 by means of V-shaped belt 77. In order to protect the operator of the machine, a guard cover 78 is secured to the side plate 50b to cover the exposed pulley 67 and belt 77 located adjacent to the outer surface of the side plate 50b.

When the motor 40 of the machine is placed in operation it rotates the driven roller 27 in a counter-clockwise direction (Figs. 1 and 2) by means of the V-shaped belt 42. The driven roller 27, by means of the V-shaped belt 77, causes the roller 63 to rotate in a counter-clockwise direction. Since the roller 63 and the roller 64 are coupled by the continuous flat belt 65, the roller 64 is also rotated in a counter-clockwise direction. In addition to the foregoing, the driven roller 27 is coupled to the pulley 35 by means of the V-shaped belt 43, and thereby causes the pulley to rotate in a counter-clockwise direction. Since the pulley 35 is rigidly supported upon the same shaft with the gear 36, the gear 36 also rotates in a counter-clockwise direction and causes the cooperating gear 37 to control the oscillations of the spreader plates 32a and 32b in the manner previously described.

With the motor 40 driving the various parts of the mechanism in the manner described above, the machine is in condition to receive a roll of soiled toweling and to unwind and fold the same into predetermined flat layers. When the operator inserts a roll of soiled toweling 53 through the opening provided in the top of the machine it may be dropped or placed in the V-shaped trough formed by the surfaces 56b and 56c in the gate 56.

In depositing the soiled toweling 53 into the opening in the machine the operator must also hold the leading edge of the outer web of the toweling and insert the same between the adjacent surfaces of the driven roller 27 and the pressure roller 30, so that the outer web of the toweling will be pulled from the roll 53 in a clockwise direction, as seen in Figs. 1 and 2.

As soon as the weight of the roll of toweling 53 is placed upon the V-shaped trough of the gate 56 the tension of the springs 61a and 61b will be sufficiently overcome to permit the gate assembly, including the gate mounting 55 and the gate 56, to rotate in a clockwise direction about the pivot pins 60a and 60b. The clockwise rotation of the gate assembly will be terminated as soon as the gate assembly engages the stop pins 62a and 62b. When this occurs the surface 56b of the gate 56 will be in alignment with the upper surface of the roll supporting bottom cover 52. Due to the inclined plane of the two surfaces, as is clearly illustrated in Fig. 2, the roll 53 will roll from the surface 56b on the gate 56 to the roll supporting bottom cover 52. As soon as the weight of the roll 53 leaves the surface 56b of the gate 56, the springs 61a and 61b will immediately restore the gate 56 to the closed position, illustrated by the full lines thereof in Fig. 2. It may be well to mention at this time, however, that as the gate 56 is tilted by the weight of the roll 53 a peripheral portion of the surface of the roll 53 may engage the lower portion of the moving continuous flat belt 65. Since the belt 65 is rotated in a counter-clockwise direction it will act upon the periphery of the roll 53 to rotate the same in a clockwise direction and it will also drive the gate assembly to the open position so that the roll 53 will assume the position illustrated by the full lines in Fig. 2.

At this time the outer web of the roll 53 will be pulled from the roll over the surface 56d on the gate 56, which functions to smooth out wrinkles in the toweling, and then over the upper surface of the combination roll panel and towel guide member 61 and then downwardly between the driven roller 27 and the pressure roller 30. As the web of the roll toweling falls between the oscillating spreader plates 32a and 32b it will be directed so that it automatically falls in folded layers upon a suitable work surface (not shown). It should be noted, however, that the driven roller 27 and the pressure roller 30 cooperate, so that the web of toweling is pulled from the roll 53.

During the unwinding operation described above, the gate assembly will normally retain the roll 53 in the position illustrated. However, if adjacent layers of the toweling are stuck together by dried grease, dirt, blood, etc., the pull of driven roller 27 on the outer web of the toweling may cause the roll to be pulled up the inclined surface 56d of the gate 56. However, as soon as the roll 53 is pulled up the inclined surface 56d sufficiently to cause the upper peripheral surface of the roll to engage the lower surface of the rotating continuous flat belt 65, the counter-clockwise rotation of the belt 65 will cause the roll 53 to be rotated in a clockwise direction. The joint action of the pulling of the web of the roll 53 by the driven roller 27 and the clockwise rotation of the roll 53 by the belt 65 will pull the outer web of the roll away from the next layer thereof in order to break apart the stuck together layers and will also cause the roll 53 to again assume its normal position upon the bottom cover 52, as illustrated in Fig. 2.

If, during the above described unwinding operation, the roll 53 is diminished in size sufficiently to permit the same to be pulled up the inclined surface 56b a considerable distance, the gate 56, due to the inclined surface 56d, will direct the upper peripheral surface of the roll 53 in engagement with the moving continuous flat belt 65, and thereby cause the roll to be rotated in the

manner previously explained. Accordingly, the unwinding of the web of toweling from the roll 53 will normally be accomplished by the sole action of the driven roller 27 pulling upon the outer web of the roll but whenever the roll is pulled up the surface 56d of the gate and engages the belt 65, the unwinding operation will be accomplished by the joint action of the driven roller 27 pulling upon the outer web of the roll and the belt 65 rotating the roll 53.

While one embodiment of the invention has been disclosed, it will be understood that various modifications may be made therein which are within the true spirit and scope of the invention.

What is claimed is:

1. In a machine for unwinding a roll of textile material, a roll support for loosely supporting a roll of textile material, a driven roller, means including said driven roller for unwinding said material from said roll by pulling upon the outer web thereof, and additional means for automatically rotating said roll in the event said roll is dislodged from its resting position on said roll support by said unwinding means.
2. In a machine for unwinding a roll of textile material, a roll support for loosely supporting a roll of textile material, a driven roller, means including said driven roller for unwinding said material from said roll by pulling upon the outer web thereof, and additional means for automatically restoring said roll to said roll support in the event it is pulled away therefrom by said unwinding means.
3. In a machine for unwinding a roll of textile material, a roll support for loosely supporting a roll of textile material, a driven roller, means including said driven roller for unwinding said material from said roll by pulling upon the outer web thereof, a moving belt, and means included in the path over which the web of said material is pulled from said roll for directing said roll into engagement with said moving belt in the event the outer web of said material fails to unwind from said roll, whereby said moving belt rotates said roll in a direction to impart rotary motion to said roll in said unwinding direction.
4. In a machine for unwinding a roll of textile material, a roll support for loosely supporting a roll of textile material, a driven roller, means including said driven roller for unwinding the said material from said roll by pulling upon the outer web thereof, thereby to rotate said roll on said roll support in a predetermined direction, a moving belt, and means positioned in the path over which the outer web of said material is pulled from said roll for directing a portion of the outer surface of said roll into engagement with said moving belt in the event the outer web of said material fails to unwind from said roll and said roll is thereby dislodged from said roll support in order to drive said roll in said predetermined rotary direction and to restore said roll to said roll support.
5. In a machine for unwinding a roll of textile material, a roll support for loosely supporting a roll of textile material, a driven roller, means including said driven roller for unwinding said material from said roll by pulling upon the outer web thereof, thereby to rotate said roll in a predetermined direction, a smoothing member arranged parallel to said roll support over which the outer web of said material is pulled by said unwinding means, a moving belt, and an inclined surface on said smoothing member for directing said roll into engagement with said

moving belt in the event the outer web of said material fails to unwind from said roll and said roll is thereby dislodged from its loosely supported position on said roll support and pulled up said inclined surface, whereby said moving belt rotates said roll in said predetermined direction in order to restore said roll to said roll support.

6. In a machine for unwinding a roll of textile material, a gate member including a roll receiving trough biased to a first position and movable to a second position, a roll support, a roll receiving opening in said machine through which a roll of textile material is inserted and placed upon said trough of said gate member, the weight of said roll upon said trough actuating said gate member from its first position to its second position so that said roll is transferred from trough to said roll support, and means for unwinding said material from said roll by pulling upon the outer web thereof.

7. In a machine for unwinding a roll of textile material, a gate member including a roll receiving trough biased to a first position and movable to a second position, a roll support, a roll receiving opening in said machine through which a roll of textile material is inserted and placed upon said trough of said gate member, said gate member being moved from its first position to its second position against said bias in response to the placement of said roll upon said trough, said roll being dislodged from said trough and deposited upon said roll support in the second position of said gate member, said gate member thereafter returning to its first position in order to restrain accidental displacement of said roll from said roll support, and means for unwind said material from said roll by pulling upon the outer web thereof.

8. In a machine for unwinding a roll of textile material, a gate member including a roll receiving trough portion and a web smoothing surface, said gate being biased to a first position and movable to a second position, a roll support, a roll receiving opening in said machine through which a roll of textile material is inserted and placed upon the trough portion of said gate member, the weight of said roll being such that said gate is moved from its first to its second position against said bias, said roll being rolled from the trough portion of said gate member to said roll support in the second position of said gate so that said gate returns to its first position, and means for rotating said roll on said roll support by pulling the outer web of the material from said roll over said web smoothing surface of said gate member.

9. In a machine for unwinding a roll of textile material, a gate member including a roll receiving trough biased to a first position and movable to a second position, a roll support, a roll receiving opening in said machine through which a roll of textile material is inserted and placed upon said trough of said gate member, said gate member being moved from its first position to its second position against said bias in response to the placement of said roll upon said trough, said roll being dislodged from said trough and deposited upon said roll support in the second position of said gate member, said gate member thereafter returning to its first position in order to restrain accidental displacement of said roll from said roll support, and means for unwinding said material from said roll by pulling the outer web thereof over said gate member in order to

prevent the placement of another roll upon said trough.

10. In a machine for unwinding a roll of textile material, a gate member including a roll receiving trough biased to a first position and movable to a second position, a roll support, a roll receiving opening in said machine through which a roll of textile material is inserted and placed upon said trough of said gate member, the weight of said roll upon said trough actuating said gate member from its first position to its second position so that said roll is transferred from trough to said roll support, a driven roller, means including said driven roller for unwinding said material from said roll by pulling upon the outer web thereof, and additional means for automatically unwinding said roll in the event said roll is pulled from roll support by said unwinding means.

11. In a machine for unwinding a roll of textile material, a gate member including a roll receiving trough biased to a first position and movable to a second position, a roll support, a roll receiving opening in said machine through which a roll of textile material is inserted and placed upon said trough of said gate member, said gate member being moved from its first position to its second position against said bias in response to the placement of said roll upon said trough, said roll being dislodged from said trough and deposited upon said roll support in the second position of said gate member, said gate member thereafter returning to its first position in order to restrain accidental displacement of said roll from said roll support, a driven roller, means including said driven roller for unwinding said material from said roll by pulling upon the web thereof, a moving belt, and means for directing said roll against said moving belt in the event it is pulled from said roll support by said unwinding means, whereby said moving belt rotates said roll in the unwinding direction in order to restore said roll to said roll support.

12. In a machine for unwinding a roll of textile material, a gate member including a roll receiving trough portion and a web smoothing surface, said gate being biased to a first position and movable to a second position, a roll support, a roll receiving opening in said machine through which a roll of textile material is inserted and placed upon the trough portion of said gate member, the weight of said roll being such that said gate is moved from its first to its second position against said bias, said roll being rolled from the trough portion of said gate member to said roll support in the second position of said gate so that said gate returns to its first position, means for rotating said roll in said roll support by pulling the outer web of the material from said roll over said web smoothing surface of said gate member, a moving belt, and means including said web smoothing surface of said gate member for directing said roll against said moving belt in the event a portion of the outer web of said roll is stuck to the next adjacent layer of said roll and said roll is thereby pulled from said roll support by said unwinding means, said moving belt thereupon rotating said roll in said unwinding direction so that the joint action of the pull on the outer web of said roll and the rotation of said roll by said moving belt breaks said stuck outer web away from said adjacent layer and restores said roll to said roll support.
